UNITED STATES PATENT OFFICE.

HARRY C. HOWER, OF CHICAGO, ILLINOIS.

DESIGN FOR AN AUTOMOBILE TIRE.

Application filed May 28, 1923. Serial No. 6,300. Term of patent 3½ years.

To all whom it may concern:

Be it known that I, HARRY C. HOWER, a citizen of the United States, residing at Chicago, in the county of Cook and State of Illinois, have invented a new, original, and ornamental Design for Automobile Tires, of which the following is a specification, reference being had to the accompanying drawing, forming a part thereof.

In the drawing,

Fig. 1 is a plan view of a portion of the tire;

Fig. 2 is a side elevation of the same;

Fig. 3 is a transverse radially disposed section on the line 3—3 of Fig. 1; and

Fig. 4 is a perspective view of the tire.

I claim:

The ornamental design for an automobile tire, as shown.

HARRY C. HOWER.
